INVENTOR

John Baunach,

BY Drake & Co. ATTY'S.

UNITED STATES PATENT OFFICE.

JOHN BAUNACH, OF NEWARK, NEW JERSEY.

TRAVELING-BAG FASTENING.

SPECIFICATION forming part of Letters Patent No. 444,205, dated January 6, 1891.

Application filed May 31, 1890. Serial No. 353,801. (No model.)

To all whom it may concern:

Be it known that I, JOHN BAUNACH, a citizen of the United States, residing at Newark, in the county of Essex and State of New Jersey, have invented certain new and useful Improvements in Snap-Catches; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a snap catch or fastener for satchels and bags which shall be comparatively inexpensive and simple in construction, as well as effective and automatic in operation.

The invention consists in the improved catch or fastener and in the arrangement and combination of the several parts thereof, as hereinafter shown and described, and finally pointed out in the claim.

Referring to the accompanying drawings, in which like letters of reference indicate corresponding parts wherever they occur, Figure 1 represents in elevation an ordinary bag-frame with my improved snap-catch attached thereto. Fig. 2 is an end view of the same, showing the jaws opened and exposing a portion of said catch secured to one of said jaws. Fig. 3 is a detail of said portion. Fig. 4 is a central longitudinal section of the parts which are secured to the opposite jaw. Fig. 5 represents in a top, edge, and end view the catching-lever; and Fig. 6, a plan and edge view of the spring employed in my device.

In said drawings, *a* indicates the case, in which certain parts of the catching mechanism are inclosed, and which is secured to the outer jaw of the bag-frame, in the present instance at the corners thereof.

b and *c* indicate the finger-piece and tail-piece, respectively, which constitute the catching-lever, which is provided with laterally-extending journals *d*. Said tail-piece projects approximately at a right angle from said finger-piece, the journals being located at or near the junction of the two parts, as indicated in Fig. 4. Said finger-piece is located outside of the inclosing case *a*, and the

tail-piece projects through said case and through the bag-frame, as shown, apertures being formed in the said parts for the purpose. The pivots or journals *d* also have 55 their bearings inside of the case, as shown.

e indicates a spring, which lies inside the case and is preferably secured thereto, and has an aperture or opening therein, through which said tail-piece passes, and which allows 60 the spring to bear firmly upon the journals or pivots *d*, which are so faced where the spring lies upon them as that said spring serves to hold the catch both in its open and closed position, as will be understood. It will be evident, however, that the spring may be secured 65 to the bag-frame or lie loose in the case, if preferred, and perform the same functions.

g indicates lugs projecting from the ends of the case, by means of which, in the present 70 instance, the case is secured to the bag-frame, they being passed through apertures therein and clinched upon the inside thereof, thus forming a very convenient, cheap, and secure fastening.

h and *i* indicate two hooks, which are firmly secured to the jaw of the frame opposite to that on which the case is secured, one of which *i* automatically engages in holding relation with the tail-piece when the bag is closed, 80 and the other engages automatically with said tail-piece when the bag is opened and throws it again in position to engage the hook *i* when the bag is closed, as will be understood. When the finger-piece is thrown upward to 85 release the catch or tail-piece to open the bag, said tail-piece is thereby thrown into position to be engaged by the hook *h*, when the bag is opened, as above described. By this arrangement and operation of the parts the catch is 90 prevented from being left open by accident or carelessness, as will be obvious. It will be observed that the finger-piece is so adjusted in relation to the case as that the end thereof can be conveniently seized by the fingers to 95 raise it up when opening the bag, as will be understood.

Having thus described my invention, what I claim as new, and desire to secure by Letters Patent of the United States, is—

A snap-catch for bag-frames, consisting of a case adapted to be secured to the outside

jaw of said frame, a finger-piece carrying a tail-piece and laterally-projecting pivots or journals, said finger-piece lying outside of said case and the tail-piece passing through said case and bag-frame, and said pivots having their bearings inside of said case, a spring arranged to bear upon said pivots to hold the parts in an open or closed position, two oppositely-projecting hooks secured to the inner jaw of said bag-frame, one of which is adapted to automatically engage in holding relation with said tail-piece when the bag is closed, and the other when the bag is being opened,

to automatically engage with and throw said tail-piece back into position to engage again 15 with the opposite hook when the bag is being closed, substantially as described, for the purposes set forth.

In testimony that I claim the foregoing I have hereunto set my hand this 24th day of 20 May, 1890.

JOHN BAUNACH.
